UNITED STATES PATENT OFFICE

THOMAS M. ROYAL, OF PHILADELPHIA, PENNSYLVANIA, ASSIGNOR, BY MESNE ASSIGNMENTS, TO ROYAL-ALLEN-MAIR, INC., OF DOVER, DELAWARE, A CORPORATION OF DELAWARE

BAG

Application filed April 11, 1928, Serial No. 269,231, and in Great Britain February 11, 1928.

My invention relates to the manufacture of bags and like containers and comprises an improved construction involving the production of a substantially continuous composite sheet or web from which bag blanks are formed; such sheet having a transparent portion continuous therewith whereby bags produced therefrom may have, either upon one or a plurality of sides thereof, a full length transparent area or zone which will permit inspection of the contents of said bag without the necessity of opening the same.

The composite bag-forming material may be made of a section or sections of any suitable form of paper, fabric or the like, in any suitable width, combined with a section or sections of transparent material of suitable width whereby such composite sheet is provided with a transparent zone or area or with transparent zones or areas, and for this purpose I have combined one or more sections of paper or the like, with one or more sections of a perfectly transparent film or pellicle which may be of any well known cellulosic type, "cellophane" for instance, or any other suitable and substantially similar material.

The principal object of my invention is to produce containers in the form of bags from such improved composite sheet material, which includes at least one part or section which is transparent, preferably highly so, while the other part thereof consists of strips of paper or other suitable material; such bags being preferably formed upon machines of the usual or ordinary type and the transparent material employed being susceptible of manipulation by the bag-forming means of such machines without damage or deformation. Bags of such construction are available for use in the packaging of many articles of food, delicate fabrics, and other vendible articles and where, for any reason, it is desirable that the contents of the container may be viewed and examined through one or more walls thereof without destruction or removal and without handling the article or articles within such container.

These and other features of my invention are more fully described hereinafter; refer-

ence being had to the accompanying drawings, in which:

Figure 1 is a perspective view illustrating a portion of one form or type of composite sheet material from which bags embodying my invention may be made.

Figs. 2 and 3 are similar views illustrating other types of composite sheet material from which bags within the scope of my invention may be made.

Fig. 4 is a diagrammatic view illustrating one manner of assembling and joining together separate strips of material to form a composite sheet from which my improved bags may be made.

Figs. 5 and 6 are perspective views of bags within the scope of my invention made from one form of composite sheet material, and

Fig. 7 is a perspective view of another construction of bag within the scope of my invention.

Bags having a single transparent portion or zone which extends throughout the length of the wall of such bag or other similar container, will have a distinct value in that the presence thereof will permit inspection of the contents and enable the purchaser to be apprised of the character thereof without handling the same and thereby soiling the fingers. Such condition is fulfilled if only a continuous portion of one side or wall of the bag is transparent and my invention includes a bag having one wall; a continuous portion of one wall, or a plurality of its walls, provided with zones or areas of transparent material which extend throughout the length of the bag.

In order that the structure of my improved bag may be more clearly understood and the manner in which it is made fully indicated I have illustrated and will describe different constructions of composite sheet material of which bags embodying my invention may be made. This material as illustrated consists of strips of paper and either of one strip of transparent material as illustrated in Fig. 1, or a plurality of strips of transparent material as illustrated in Fig. 2. Such composite sheet material is preferably formed from independent strips of material, trans-

parent and otherwise, which may be delivered from suitable rolls in such manner and in such relation to each other that adhesive applied to certain edge portions of said strips will effect permanent connection of the same when the said edges are brought into overlapping relation and preferably subjected to suitable pressure. It is essential that the composite material from which my improved bags are made is of a character that may be readily and successfully passed through bag-forming machines of the usual type. In practice, the composite sheet material is delivered to the tube-forming mechanism of bag-machines wherein the outer free edges of the composite sheets are brought into overlapping position and secured together by suitable adhesive in the usual manner.

In Fig. 1, of the drawings I have illustrated one form of a composite sheet from which my improved bags may be made comprising strips of suitable material, paper of any suitable type, indicated at A, A, with an intermediate strip B, of transparent material, which may be the "cellophane" of commerce, or any similar transparent strip, having its edges permanently secured to the edges of said strips A, A. This view illustrates the edges of the transparent strip B as underlying the edges of the laterally disposed strips A, A, although it will be understood that this arrangement may be reversed, if desired.

In Fig. 2, I have shown another form of composite sheet material which may be made up of more than two strips of paper or like material, in this instance three, indicated at A', A', A', and more than one strip of transparent material, in this instance two, indicated at B', B'.

In Fig. 3 I have shown a composite sheet of bag-forming material made up of a single strip of paper or similar material A², and a single strip of the transparent material, indicated at B², which may be employed for the making of bags within the scope of my invention.

In Fig. 4 I have illustrated, diagrammatically, one manner in which the composite sheet of bag-forming material illustrated in Fig. 1 may be produced; 1 and 2 representing rolls of paper, fabric or other suitable material, delivering the strips indicated at A, A, and 3 a roll delivering the strip of transparent material, indicated at B. Suitable adhesive-applying disks 4 disposed in a receptacle 5, may be arranged to engage the edges of the strips A, A, and apply a film of adhesive whereby they may be joined to the edges of the intermediate transparent section B; the several connected strips forming the composite sheet material preferably passing between a pair of rolls 8 and 9, whose pressure will insure permanent adhesion of the edges.

Although I have described the composite

sheet material from which my improved bags are made as being formed or manufactured upon machines—and in commercial practice the use of machines would be necessary—yet insofar as my present invention is concerned it is immaterial whether such composite sheet material be formed or manufactured upon a machine or whether it be produced manually.

The bags shown at C, in Figs. 5 and 6, are of a type mechanically produced, and while bags may be made from any form of my improved composite material, those shown in said views are represented as made from composite sheet material of the character illustrated in Fig. 1; the bag shown in Fig. 5, having its continuous transparent area or zone b centrally disposed, while the bag shown in Fig. 6, has its continuous transparent area or zone b' at one side of its face. In the latter form, the space adjacent the continuous transparent portion of the bag face may receive printed matter indicating the contents of the bag, or other information, although it will be understood that such transparent material may also receive printed matter.

The package D, illustrated in Fig. 7, comprises a bag of a well known type, made of composite sheet material of the character illustrated in Fig. 2, which comprises a plurality of strips of paper or other suitable material and a plurality of transparent strips. Preferably these latter strips should be highly transparent. The transparent portions of the composite material employed for this bag are so disposed that the finished article will have oppositely disposed zones or areas b² of transparent material, extending the full length of the bag, through which the contents of such bag may be viewed; while the other walls may receive printed matter.

While I refer to the use of strips of paper in combination with strips of transparent material, it will be understood that the less transparent portion or portions of the composite sheet material from which my improved bags are made may be of any suitable strip of paper, fabric, or the like, and that the transparent portion or portions may be of any suitable material, a cellulosic or other body, "cellophane" for instance, having preferably a high degree of transparency and capable of permanent engagement with the paper or other strips constituting the other part of such composite material by the aid of a suitable adhesive.

I do not wish to be limited to the use of "cellophane" as the transparent portion of the composite bag-forming material mentioned because I may employ the so-called "crystalline" or "glassine" of commerce, or any other transparent film or pellicle which is sufficiently flexible to render it capable, when permanently associated with the other portions making up the com-

posite sheet material of passing through a bag machine of the usual or ordinary type wherein such composite sheet material may be fashioned into the usual tubes from which bags of any commercial form are produced.

5 I claim:

1. A paper bag made of a section of a composite sheet consisting of two strips of flexible material and a transparent strip of flexible material so arranged that one edge of each of the first-named strips is in opposed spaced relation to one edge of the other strip with the transparent strip located between and secured to said opposed edges; the outer 10 edges of said composite sheet being overlapped and permanently secured together in tube formation and all of the strips of said composite bag being of substantially the same length.

20 2. A paper bag made of a composite sheet developed into tubular form; said composite sheet comprising a plurality of strips of flexible material and a transparent strip of flexible material in parallel relation; said 25 strips being so arranged that one edge of one of the first-named strips is in opposed spaced relation to one edge of another of said strips with the transparent strip located between said opposed edges and united thereto; the outer edges of said composite 30 sheet being overlapped and permanently secured together in tube formation and all of said strips being of substantially the same length.

35 3. A paper bag made from a tubular portion of a continuous composite structure consisting of a plurality of strips of suitably flexible material secured together in parallel relation; one of said strips being transparent and the several strips being of substantially equal length and said tubular portion having a folded end secured to one wall of the same.

40 4. A bag comprising strips of transparent and less transparent flexible material of equal length having their longitudinal edges united and forming a tubular structure, one end of which is flattened and folded back against the outer wall of the tubular structure and secured thereto, the transparent strip being located substantially centrally in one face of the bag formed by flattening said tubular structure and folding back and securing the same.

45 5. A bag for holding and displaying contained articles, comprising alternate strips of transparent and opaque material of substantially equal length, a transparent strip being located between and secured to one edge of each two opaque strips, the other edges of the opaque strips being secured together forming a tubular structure, and one end of said tubular structure being folded back and secured to the adjacent outer surface of said 50 tubular structure thereby locating the trans-

parent strip centrally of and extending the full length of one face of the bag.

6. A bag for holding and displaying contained articles, comprising transparent and opaque strips of substantially equal length secured together in overlapping relation, a transparent strip being located between and secured to the edges of said opaque strips, said article having the free edges of its opaque strips secured together and the material at one end folded back and secured to the back of the structure forming a bag with a transparent face exposed the full height of the bag.

70 In witness whereof I have signed this 80 specification.

85 THOMAS M. ROYAL.
